MAGAZINE PHONOGRAPH

George Stanley Mann, Ipswich, England

Application September 21, 1938, Serial No. 231,083
In Great Britain September 29, 1937

10 Claims. (Cl. 274—10)

This invention relates to magazine phonographs of the kind having means for automatically and successively transferring the records to be played from a magazine or pile to the turntable. With such arrangements each played record either remains on the turntable, which is depressed to permit receiving a fresh record (such as the phonograph described in the specification of applicant's British Patent No. 472,135) 5 published October 14, 1937 and sealed December 9, 1937) or is removed from the turntable to a "discarded" well for played records (such as described in the specification of applicant's British Patent No. 402,779 published January 4, 1934 and sealed November 8, 1934), the magazine or record-storage platform being raised step by step as each top record is removed.

It is the primary object of the present invention to provide simple but effective means for determining and controlling the proper position of the top record on the record-storage platform and for locking or retaining said platform in position between successive lifting movements.

In order that the invention can be fully appreciated, one preferred embodiment thereof will now be described with reference to the accompanying drawing, wherein:

Fig. 1 shows somewhat diagrammatically a plan view of a magazine phonograph according to the invention,

Fig. 2 shows, also diagrammatically, a sectional elevation of Fig. 1, and

Fig. 3 shows a schematic view of the hydraulic fluid system incorporated in the arrangement shown in Figs. 1 and 2.

This particular embodiment of the invention is carried out in connection with a magazine phonograph of the kind wherein the records are transferred to a depressible turntable 5 upon which the records are played and the played records stored, the arrangement being such as that described in applicant's British specification No. 472,135.

The records to be played are housed in a pile 45 in a compartment or well of the phonograph cabinet and they rest upon a platform 6 mounted upon the upper end of a vertical guide sleeve 7 sliding over a central vertical rod 8 fixed at its lower end to the base of the cabinet. Said sleeve 7 is in two screwed-together adjustable parts to allow for alteration of its length and is suitably guided in a bearing 9 carried by a cross member 10 of the cabinet.

The upper end portion of the vertical rod 8 50 extends through the record-storage platform 6

and forms a pin upon which records 11 are centered.

A coiled spring 12 supported on the cross member 10 of the cabinet acts upon the underside of the platform 6 and tends to raise the said platform and the records thereon. 5

The turntable 5 is adapted to be depressed to carry the played records 11' and is interconnected with the record-storage platform 6 so as to descend as said platform rises, being used 10 in conjunction with a single record-lifting or transferring device, such as a single horizontally swinging arm carrying an electro-magnet, as described in applicant's British specification No. 472,135 and as indicated at 13. 15

The turntable 5 is mounted within a well or chamber of the phonograph cabinet and is carried by the upper end of a central vertical sleeve 14 which is slidable and rotatable over a vertical centre guide rod 15 fixed at its lower end to the base of the cabinet. The upper end of this rod 15 serves to receive the records 11'. 20

The sleeve 14 is adapted to be rotated by a motor unit 16 through the intermediary of a sliding coupling device so that the turntable 5 25 can be driven while at any height.

The lower end of the turntable sleeve 14 is coupled, by a pin and slot connection, to one end of a two-armed lever system 17 the other arm of which is similarly coupled by a pin and slot connection to the lower end of the sleeve 7 of the record-storage platform 6. 30

The lever system 17 is fulcrumed at its middle upon a bracket 18 and moves in a vertical plane.

It will be readily appreciated that by reason of this lever connection, the turntable 5 descends to a distance equal to the thickness of a record while the record-storage platform 6 rises a similar amount, said latter platform being constantly urged upwards by means of its spring 12 assisted 40 by the weight of any records such as 11' on the turntable 5.

In order to control the lifting of the platform 6 and the corresponding depression of the turntable 5 and also to determine the correct position of the top record upon the platform 6, that arm of the lever system 17 which is nearest the turntable is connected by an upwardly directed link 19 to the upper end of a piston rod 20 which carries at its lower end a piston 21 working 45 within a vertical cylinder 22 adapted to be filled with oil or other suitable hydraulic fluid.

The upper and lower ends of the cylinder 22 are connected by a conduit 23 within the length of which there is provided a valve box 24. 50

Upon particular reference to Fig. 3 of the drawing it will be observed that this valve box encloses a vertically disposed valve 25 which is normally held closed against a co-operating seating by means of a spring 26 so that normally the conduit is closed and the flow of hydraulic fluid from one side to the other of the cylinder 22 is prevented.

Consequently, although the piston 21 is constantly urged downwards by reason of its connection with the lever system 17, it cannot descend and displace the fluid below it so long as the valve 25 remains closed and thus the platform 6 cannot rise.

15 In order to move the valve 25 from its co-operating seating when the top record on the storage platform 6 is removed, a horizontal control arm or lever 27 is provided and is adapted to rest upon the top record on the platform 6. 20 This control arm 27 is pivoted at its inner end to a bracket 28 mounted on the phonograph cabinet and such as to turn in a vertical plane. The outer or free end of this control arm, which lies over the top record near the centre thereof, 25 is weighted so that the arm rests on said record.

Furthermore, near the pivoting point of the said control arm 27 is provided an adjustable screw 29 which is adapted to abut against the upper end of a vertical push rod 30 whose lower end extends into the valve box 24 and is adapted to engage with the valve 25.

30 So long as the top record on the platform 6 is at its correct height, the control arm 27 resting thereon occupies a relatively raised position and the push rod 30 merely rests lightly on the valve 25 without any pressure being applied to it by the arm.

When, however, the top record has been transferred to the turntable through the intermediary 40 of the transfer arm indicated at 13, the control arm 27 falls on the next record and in doing so its weight thrusts the push rod 30 downwards against the valve 25 which is thus forced from its seating against the action of the spring 26. Thus, 45 the conduit 23 is opened to permit the passage of fluid from one end to the other of the cylinder 22 and allow the piston 21 to descend a short distance in its cylinder and the platform to rise.

The control arm 27 will also be raised by the 50 next top record and when this record reaches its predetermined correct height for transfer the control arm will have risen to its initial position and, relieving the pressure on the push rod 30, will release the valve 25 which, under the action 55 of the spring 26, will again close the conduit 23, thus preventing further movement of the piston 21 and consequently further upward movement of the platform 6.

It should be noted that the piston 21 is provided 60 with a through passage controlled by a spring-loaded ball valve 31 that closes the passage during downward movement of the piston but is capable of opening said passage if the piston is moved upwards.

65 When all records have been removed from the record-storage platform 6 the piston 21 will be at the bottom of its stroke, the oil from beneath having been transferred to the top of the cylinder 22 past the control valve 26.

70 To re-load the storage platform 6, said platform is depressed (after removal of the played records from the turntable 5), causing the piston to rise to the top of its cylinder, thus transferring the oil from the top of the cylinder to the space beneath the piston past the ball valve 31.

There is indicated at 32 a pick-up arm mechanism which is preferably of the kind described in the specification of applicant's co-pending British patent application No. 26,381/37 although it is of course to be understood that any suitable pick-up or tone-arm device can be provided in conjunction with the turntable 5.

The invention is not limited to the precise forms or details of construction described, as these may be varied to suit particular cases without departing from the scope of the appended claims.

What I claim and desire to secure by Letters Patent of the United States of America is:

1. A magazine phonograph comprising, in combination, a movable record-storage platform, means for raising said platform to bring the top record thereon to a predetermined level, a chamber adapted to contain a hydraulic fluid, a member operatively connected to the platform and forming a movable wall of the said chamber, a passage-way to allow such fluid to flow from said chamber, a valve device for controlling the flow of such fluid from the chamber, movable means for contacting with the top record on the platform and a connection between said contacting means and the valve device so that upon the top record being removed from the platform the contacting means moves into contact with the next record on the platform and as a consequence opens the valve to permit the flow of hydraulic fluid from the chamber whereby the movable wall member, under the action of the means for raising the platform, can bring about a flow of hydraulic fluid from the chamber and said flow will continue until such time that the said next record has been raised to a predetermined level, whereupon the contacting means will have moved to close the valve to terminate the flow of fluid and consequently prevent further movement of the movable wall member and further raising of the platform connected thereto.

2. A magazine phonograph comprising, in combination, a movable record-storage platform, means for raising said platform to bring the top record thereon to a predetermined level, a cylinder adapted to contain a hydraulic fluid, a piston member arranged within said cylinder and operatively connected to the movable record-storage platform, a passageway to allow hydraulic fluid to flow from the cylinder, a valve device for controlling the flow of such fluid from the cylinder, movable means for contacting with the top record on the platform and a connection between said contacting means and the valve device.

3. A magazine phonograph comprising, in combination, a movable record-storage platform, means for raising said platform to bring the top record thereon to a predetermined level, a cylinder adapted to contain a hydraulic fluid, a piston member arranged within said cylinder and operatively connected to the platform, a passageway located towards one end of the cylinder to allow such fluid to flow from the cylinder, a passageway located towards the other end of the cylinder to allow such fluid to flow to the cylinder, said passageways leading to opposite sides of a valve device which is adapted to control the flow of the fluid from one side of the piston member to the other when the said member moves in one direction.

4. A magazine phonograph comprising, in combination, a movable record-storage platform, means for raising said platform to bring the top

record thereon to a predetermined level, a cylinder adapted to contain a hydraulic fluid, a piston member arranged within said cylinder and operatively connected to the platform, a passageway located towards one end of the cylinder to allow such fluid to flow from the cylinder, a passageway located towards the other end of the cylinder to allow such fluid to flow to the cylinder, said passageways leading to opposite sides of a valve device which is adapted to control the flow of the fluid from one side of the piston member to the other when the said piston member moves in one direction and a one-way valve means located in the piston member so that upon movement of the piston member in the other direction fluid can pass from one side of the piston to the other.

5 5. A magazine phonograph comprising, in combination, a movable record-storage platform, means for raising said platform to bring the top record thereon to a predetermined level, a chamber adapted to contain a hydraulic fluid, a member operatively connected to the platform and forming a movable wall of the said chamber, a passageway to allow such fluid to flow from said chamber, a valve device for controlling the flow of such fluid from the chamber, a pivoted arm whose outer end is adapted to rest upon the top record on the platform and a mechanical connection between said pivoted arm and the valve device.

10 6. A magazine phonograph comprising, in combination, a movable record-storage platform, a movable turntable upon which records are adapted to be played and such played records stored, a two-armed lever system interconnecting said platform and the turntable, means for raising the platform and consequently lowering the turntable in order to bring the top records thereon to a predetermined level, a chamber 15 adapted to contain a hydraulic fluid, a member operatively connected to the platform and forming a movable wall of the said chamber, a passageway to allow such fluid to flow from said chamber, a valve device for controlling the flow of such fluid from the chamber, movable means for contacting with the top record on the platform and a mechanical connection between said contacting means and the valve device.

20 7. A magazine phonograph comprising, in combination, a movable record-storage platform, a movable turntable upon which records are adapted to be played and such played records stored, a two-armed lever system interconnecting said platform and the turntable, means for raising the platform and consequently lowering the turntable in order to bring the top records thereon to a predetermined level, a cylinder adapted to contain a hydraulic fluid, a piston member arranged within said cylinder and operatively connected to the two-armed lever system, a passageway to allow hydraulic fluid to flow from the cylinder, a valve device for controlling the flow of such fluid from the cylinder, a pivoted arm

whose outer end is adapted to rest upon the top record on the platform and a mechanical connection between said pivoted arm and the valve device.

25 8. A magazine phonograph comprising, in combination, a movable record-storage platform, a movable turntable upon which records are adapted to be played and such played records stored, a two-armed lever system interconnecting said platform and the turntable, means for raising the platform and consequently lowering the turntable in order to bring the top record on each to a predetermined level, a chamber adapted to contain a hydraulic fluid, a member forming a movable wall of said chamber and mechanically connected to the two-armed lever system so that said movable wall member constantly exerts a pressure on the hydraulic fluid in the chamber, a passageway to allow hydraulic fluid to flow from the chamber, a valve device for controlling the flow of such fluid from the chamber, movable means for contacting with the top record on the platform and a mechanical connection between said contacting means and the valve device.

30 9. A magazine phonograph comprising, in combination, a two-armed lever system, a movable record-storage platform connected to one arm of said lever system, a movable turntable connected to the other arm of the said lever system and upon which turntable records are adapted to be played and such played records stored, means for raising the platform and consequently, as a result of the two-armed lever system, lowering the turntable in order to bring the top record on each to a predetermined level, a cylinder adapted to contain a hydraulic fluid, a piston member arranged within said cylinder and mechanically connected to the two-armed lever system so that said piston constantly exerts a pressure on the hydraulic fluid in the cylinder, a passageway located towards one end of the cylinder to allow hydraulic fluid to flow from the cylinder, a passageway located towards the other end of the cylinder to allow such fluid to flow to the cylinder, said passageways communicating through the intermediary of a valve device which serves to control the flow of fluid from one side of the piston member to the other when the said piston member moves in one direction, a pivoted arm whose outer end is adapted to rest on the top record on the platform, a mechanical connection between said pivoted arm and the said valve device, and a one-way valve means located in the piston member so that upon movement of the piston member in the other direction fluid can pass from one side of the piston to the other independently of the first-mentioned valve device.

35 10. A magazine phonograph as claimed in claim 1, including spring means for exerting a raising influence on the movable record-storage platform.

GEORGE STANLEY MANN.
